ALBERT GEE, OF OAK LANE, PENNSYLVANIA, ASSIGNOR OF ONE-HALF TO WILLIAM PARK MOORE, OF ELKINS PARK, PENNSYLVANIA.

PATTERN-CONTROLLED STOP MECHANISM FOR KNITTING-MACHINES.

1,110,322.

Specification of Letters Patent.

Patented Sept. 15, 1914.

Application filed March 30, 1914. Serial No. 828,297.

To all whom it may concern:

Be it known that I, ALBERT GEE, a citizen of the United States, residing at Oak Lane, in the county of Montgomery and State of Pennsylvania, have invented certain new and useful Improvements in Pattern-Controlled Stop Mechanism for Knitting-Machines, of which the following is a specification.

My invention has relation to a pattern controlled stop mechanism for a knitting machine so arranged as to regulate the length of the stocking and automatically to control such length of the stocking in the knitting thereof and in stopping of the machine to prevent back-lash, to thereby avoid breaking or twisting of sinkers and needles of the machine.

My invention stated in general terms, consists of mechanism constructively arranged and applied to preferably a flat knitting machine in substantially the manner herein-after described and claimed.

The nature, scope and particular features of the mechanism embodying my said invention, in a preferred form thereof, will be more fully understood from the following description taken in connection with the accompanying drawings forming part hereof, in which

Figure 1, is a front elevational view of a portion of a well known type of flat knitting machine with the mechanism in part for automatically controlling the length of the hosiery in the knitting thereof in conjunction with the other part of the mechanism designed to prevent back-lash in the stopping of the knitting machine, embodying in constructive detail the essential main features of my said invention. Fig. 2, is a vertical sec-

tional view on the line $x-x$, of Fig. 1, looking to the right, of the said automatic controlling mechanism. Fig. 3, is a vertical section on the line $y-y$, of Fig. 1, looking to the left, of the said mechanism. Fig. 4, is a

fragmentary detail in elevation and on an enlarged scale of the ratchet members of said mechanism. Fig. 5, is a vertical sectional view in detail of the ratchet members of Fig. 4. Fig. 6, is a vertical sectional view in detail on the line $z-z$, of Fig. 1, illustrating the member to prevent back-lash of said mechanism. Fig. 7, is a detail sectional elevation of one of the pins of the pawl device of the member to prevent back-lash. Fig. 8, is a

perspective view of the locking device con-

nected with a shifting lever for stopping the knitting machine; and Figs. 9 and 10, are respectively perspective views of lugs mounted on plates connected with a sprocket-chain to control the length of the stocking being knit as well as the stopping of the machine, which latter in turn controls thereby automatically any tendency to back-lash of the machine.

Referring to the drawings A, is one of the end frames and A' , a cross-frame connected therewith of a well known type of flat knitting machine and which machine to such extent only has been shown as necessary, to illustrate the application of my present invention thereto.

a , is the main driving shaft of the machine and a^2 , the cam-shaft, both journaled in the said end frames. A shifting rod a^3 , is located above the driving shaft a , and is slidably mounted in the said end frames A , for shifting the driving belt from a loose to a fast pulley, not shown, but which are mounted on the extremity of said shaft for starting and stopping the said machine. Mounted on the cross-frame A' , of the machine is a standard b , in which is fastened a stud b^1 , carrying ratchets b^2 and b^3 , and a sprocket-wheel b^4 . A chain b^5 , of any predetermined length engages a sprocket-wheel b^6 , secured to a stationary part of the knitting machine. This chain is caused to travel around the wheels b^4 and b^6 , by means to be presently more fully described. The said chain b^5 , is provided at suitable distances apart there-over, with plates b^7 , having lugs b^8 , extending vertically therefrom. These plates may be each provided with a single lug or with a series of lugs according to the particular use of the lugs, whether they are to be employed in the timing operations of the machine or for controlling automatically the length of the stocking in the knitting of the same or for preventing back-lash in the stopping of the said machine.

On the cam-shaft a^2 , is mounted a cam c , operating a roller c^1 , journaled in one member of a V-shaped bracket or rocker-arm c^2 , pivoted at c^3 , to a standard c^4 , which latter is mounted on the cross-frame A' ; the other member of the V-shaped bracket or rocker-arm c^2 , is provided with two pawls c^5 and c^6 ; said pawl c^5 , is arranged to engage the ratchet-wheel b^3 , and the pawl c^6 , is so arranged as to engage at certain times both

ratchets b^2 and b^3 . A spring c^7 , at one end is attached to the V-shaped bracket or rocker-arm c^2 , and at its other end it is attached to a stationary part of the machine. This 5 spring is provided to maintain the roller c^1 , in surface contact with the cam c , and to support the pawls c^5 and c^6 , in a position to be operative. Springs c^8 and c^9 , are connected at one of their ends with the respective 10 pawls c^5 and c^6 , and at their opposite ends to parts of the V-shaped bracket or rocker-arm c^2 . These springs normally hold the pawls in engagement with the respective ratchets b^2 and b^3 . As the cam c , is rotated 15 by the cam-shaft a^2 , the V-shaped bracket or rocker-arm c^2 , is oscillated about its pivot c^3 , so as to cause a vertical movement of the pawls c^5 and c^6 , and by engaging notches of the respective ratchets b^2 and b^3 , to cause 20 one or both ratchets to be revolved on the stud b^1 , in the direction of the arrow in Fig. 4. The ratchet b^3 , is held in frictional engagement with the ratchet b^2 , by means of the leaf spring b^9 , and is rigidly attached to 25 the sprocket-wheel b^4 , by means of bolts b^{10} . An additional friction spring b^{11} , is mounted between the sprocket-wheel b^4 , and the standard b , to hold the said sprocket-wheel free from rotation, except when positively 30 turned by the ratchet-wheel b^3 , and during the time the ratchet-wheel b^2 , is in action. The chain b^5 , is mounted on the said sprocket-wheel b^4 , and is caused to travel in the direction of the arrow in Fig. 1, so 35 as to permit the lugs b^8 , of said chain to operate to stop the machine and also to determine with precision any required length of stockings that are being knit and so that all of them will be exactly alike in length. 40 In order to avoid the use of undue length of sprocket-chain for operation, the said automatic control mechanism is provided with a ratchet-wheel b^2 , of greater diameter than the ratchet-wheel b^3 , and while having 45 the same number of teeth, one tooth b^{12} , however, of the ratchet-wheel b^2 , is of greater depth than the rest so as to allow the pawl c^6 , to engage both ratchets at the same time, when the said pawl in the travel of 50 the said ratchets reaches the said deep tooth b^{12} , of the wheel b^2 . During the knitting of a certain portion of the stocking, for instance, the welt or heel, it is unnecessary to revolve the sprocket b^4 , and which if continuously 55 revolved would require an undue length of chain and to prevent the use of such an undue length of chain, the pawl c^6 , is disengaged from the ratchet b^3 , by means of an extension b^{13} , on one of the lugs b^8 , 60 contacting with the nose of the said pawl. At the time the pawl c^6 , is disengaged the pawl c^5 , will continue to operate upon the ratchet b^2 , and revolve said ratchet independently of the ratchet b^3 , and sprocket- 65 wheel b^4 , until the deep tooth b^{12} , arrives

at a position to receive the nose of the pawl c^6 , which will now engage both ratchets causing the extension b^{13} , to move from under the pawl c^6 , to thus allow this pawl to engage the ratchet b^3 , and thereby to revolve the sprocket b^4 , thus moving the chain b^5 , until another lug b^8 , having an extension b^{13} , comes in contact with the pawl c^5 , to disengage the same. It will be understood that a series of extensions b^{13} , may be provided, one directly behind the other, so that the pawl c^5 , may be freed from operating upon the ratchet b^3 , at very close intervals, according to the work to be performed upon the stocking being knit in the machine. 70 75 80 85 90 95

In order to avoid the caution or care that at present has to be exercised by operatives in stopping the machine for any cause, for instance, either because the required welt, heel or leg has been knit, and so that they respectively will not be of unequal lengths, or one longer than the other, as is invariably the case in the operation of flat-knitting machines in the knitting of hosiery at the present time, I have provided the machine with a stop mechanism operative conjointly with the mechanism hereinbefore described for regulating and controlling automatically the exact length of any part of the stocking knit: the same consisting of means, as follows:

Certain of the lugs b^8 , on the chain b^5 , are so arranged as to contact with one end of a weighted lever d , which is pivoted at d^1 , to a standard d^2 , supported by the cross-frame A¹, the opposite end of the said lever d , being formed into a hook d^3 , engaging a complementary hook d^4 , attached to the shifting lever d^5 , having an universal connection d^6 , at the lower extremity thereof, as clearly 100 shown in Fig. 1. Opposite the cam-shaft is approximately a horizontal line therewith, the lever d^5 , has mounted thereon rollers d^7 and d^8 , contacting with a double edge cam d^9 , the edge d^{10} , of the said cam operating upon the roller d^7 , to shift the lever d^5 , to the right, for stopping the machine, while the cam edge d^{11} operates upon the roller d^8 , to return the said lever d^5 , to its initial position, being that illustrated in 105 Figs. 1 and 2, and with the machine in operation. On the shifting-rod a^3 , is mounted a U-shaped bracket e , surrounding the upper end of the shifting lever d^5 , so that when this lever is shifted to the right by the cam 110 surface d^{10} , the rod a^3 , carrying the belt shifting fork, not shown, will cause the driving belt to be shifted from a fast to a loose pulley, to free the power from operation of the machine. 115 120 125

On the shifting rod a^3 , is secured a tapered lug c^1 , which may be moved from under a finger c^2 , secured to a pawl e^8 , pivoted at c^1 , to a bar c^6 , of the machine. At the time the belt is shifted to release the 130

power, the lug e^1 , is moved from under the finger e^2 , to allow the pawl e^3 , to engage the ratchet e^4 , mounted on the driving shaft a . The teeth of this ratchet e^4 , are so arranged as that any momentum of the machine will allow it to travel in a forward direction, but through the rise of a cam or other device of the machine should any tendency to backlash occur, the pawl e^3 , will immediately engage a tooth of the ratchet e^4 , to prevent such rearward movement and thus any possibility of the sinkers, etc., being stripped or broken or the knitting needles rendered unfit for subsequent use in the machine.

15 In the pawl e^3 , is provided a plurality of pins e^5 , adjustably arranged in the extreme portion of the said pawl, so that one or the other of the series of pins is always ready to immediately engage a tooth of the said ratchet e^4 , to prevent retrograde movement thereof. To enable the machine to be quickly stopped after the belt has been shifted a leather friction or other preferred type of brake f is employed. This brake 20 surrounds the driving shaft a , and is held in engagement therewith, by means of a split collar f^1 , having ears f^2 , to receive the belts f^3 , as clearly shown in Fig. 6. This brake revolves with the shaft a , until the pawl e^3 , is allowed to engage with the ratchet e^4 , at which time a lug f^4 , mounted on the pawl e^3 , will engage one ear f^2 , of the said brake-device to cause the same to cease rotating and thus frictionally stopping the driving 25 shaft a , of the machine. The lever d^5 , is provided with two coiled springs d^6 and d^7 , having one of their extremities connected with the said framing of the machine and which springs respectively maintain the rollers d^8 and d^9 , against the working surface of the cam d^1 , at a time when the hooks d^3 and d^4 , are disengaged.

Having thus described the nature and objects of my invention, what I claim as new and desire to secure by Letters Patent is:—

1. In a knitting machine, an automatic regulating and controlling mechanism of the character described, comprising a shaft having a cam, a rocker-arm having a roller and two pawls, two ratchets, said roller actuated by said cam and said pawls at predetermined periods actuating said ratchets, a sprocket and chain, said sprocket connected with one of said ratchets and operating said chain, provided with lugs for at predetermined periods tripping one of said pawls, a pivoted shifting device controlling means to release said device and shift and reset the same and means to release the power, substantially as and for the purposes described.

2. In a knitting machine, a mechanism of the character described, comprising a rotatable cam-shaft, a rocker-arm having a roller and two pawls, two ratchets and a

sprocket connected with one of said ratchets, said cam operating said roller and said rocker-arm causing said pawls at predetermined periods to engage said ratchets, a shifting device adapted to engage means to release said device, springs for shifting and a cam for resetting said device and a sprocket-chain having a series of lugs adapted to respectively trip one of said pawls, substantially as and for the purposes described. 75

3. In a knitting machine, a mechanism of the character described, comprising a rotatable cam-shaft, a rocker-arm having a roller and two pawls, two ratchets and a sprocket connected with one of said ratchets, 80 said cam operating said roller and said rocker-arm permitting said pawls at predetermined periods to engage said ratchets, a pivoted shifting device, comprising a rocking latch-hook adapted to engage a complementary hook for releasing said device, a cam for shifting and resetting said device and a rod for transmitting motion to power means of the machine for releasing said power, substantially as and for the purposes 85 described.

4. A knitting machine having mechanism of the character described and with a shifting device, a rod operated on by said device and having a lug arranged to release a pawl 90 provided with pins and a lug, and said pins adapted to respectively engage a ratchet mounted on the main-shaft of the machine to prevent retrograde movement of the same, and a friction-brake having ears adapted to 95 engage the lug of said pawl to stop the machine, and said brake mounted on said main-shaft, substantially as and for the purposes described.

5. In a knitting machine, an automatic 100 regulating and controlling mechanism of the character described, comprising a rotatable cam-shaft, a rocker-arm having a roller and two pawls, two ratchets, one having a deep notch, a sprocket connected with one of said ratchets, said roller actuated by said cam, and said pawls at predetermined periods actuating one or both of said ratchets, a shifting device, and a chain carrying lugs 105 operating to trip one of said pawls and to shift said device, substantially as and for the purposes described.

6. In a knitting machine, an automatic 110 regulating and controlling mechanism of the character described, comprising a rotatable cam-shaft, a rocker-arm having a roller and two pawls, two ratchets, one having a deep notch, a sprocket connected with one of said ratchets, said roller actuated by said cam, and said pawls at predetermined 115 periods actuating one or both of said ratchets, a shifting device, a chain carrying lugs operating to trip one of said pawls and to shift said device and a brake frictionally connected with said main shaft and having 120

means for engaging said lugs to stop the machine, substantially as and for the purposes described.

7. In a knitting machine, a mechanism of 5 the character described, comprising a rotatable cam-shaft, a rocker-arm having a roller and two pawls, two ratchets and a sprocket connected with one of said ratchets, said cam operating said roller and said 10 rocker-arm permitting said pawls at predetermined periods to engage said ratchets, a friction device operating on one of said ratchets to maintain alining relationship of the teeth of both of said ratchets 15 and an additional frictional device operating on said sprocket to prevent rotation of said sprocket and one of said ratchets during rotation of the other of said ratchets, substantially as and for the purposes de- 20 scribed.

8. In a knitting machine, a mechanism of the character described, comprising a rotatable cam-shaft, a rocker-arm having a roller and two pawls, two ratchets and a 25 sprocket connected with one of said ratchets, said cam operating said roller and said rocker-arm permitting said pawls at predetermined periods to engage said ratchets and a shifting device and a double face cam

for controlling said device in the shifting 30 and resetting of the same, substantially as and for the purposes described.

9. In a knitting machine, a mechanism of the character described, comprising a rotatable cam-shaft, a rocker-arm having a 35 roller and two pawls, said rocker-arm having a spring for holding said roller in contact with said cam, ratchets and a sprocket operated by said ratchets, said cam operating said roller and said rocker-arm permitting 40 said pawls to engage said ratchets, a shifting device, a double face cam to shift and reset said device, a spring controlled rod carrying rollers operated on by said cam, said springs supporting said rollers in 45 contact with said cam, a latch-hook and a complementary hook arranged to engage each other to hold said shifting device away from said cam during knitting operations, substantially as and for the purposes de- 50 scribed.

In witness whereof, I have hereunto set my signature in the presence of the two subscribing witnesses hereto.

ALBERT GEE.
